OTTO HILDEBERT MUELLER, OF BERLIN, GERMANY, ASSIGNOR TO
HENRY R. WORTHINGTON, OF NEW YORK, N. Y., A CORPORATION
OF NEW JERSEY.

EQUALIZING DEVICE FOR DIRECT-ACTING ENGINES.

No. 846,045.

Specification of Letters Patent.

Patented March 5, 1907.

Application filed October 16, 1903. Serial No. 177,281.

To all whom it may concern:

Be it known, that I, OTTO HILDEBERT MUELLER, a subject of the German Emperor, residing at Berlin, W., in the German Empire, have invented certain new and useful Improvements Relating to Equalizing Devices for Direct-Acting Engines, of which the following is a specification.

This invention relates to a compensating cylinder as often applied to direct-acting pumping and blowing engines for equalizing the forces acting in the motor-cylinders.

The invention specially relates to such equalizers in which a piston acts in opposition to the movement of the engine during one part of the stroke and in conjunction therewith during another part of the stroke; and the special feature of it is that at all times it automatically accommodates itself to the requirements of the engine, so that any variations in the distribution of the motor fluid in the main engine or in the speed of it may be effected without affecting the proper running of the engine. To attain this end, the compensator consists of a cylinder closed on both ends containing a piston, the motor fluid, which may be air or gas, being continually admitted to the working side, but bypassed from time to time or in regular intervals to the opposite or counteracting side of the piston, after which the motor fluid may be exhausted to the atmosphere or admitted again to the supply-pump of the motor fluid, thus working in a circle. Further means are provided for regulating the height of the pressure of the motor fluid on both sides of the compensator-piston and for regulating the change of the pressure of the motor fluid during different parts of the stroke.

In the accompanying drawings a compensator of the above type is illustrated, Figure 1 showing a longitudinal section through it; Fig. 2, a horizontal cross-section on the line A A, and Fig. 3, Fig. 4, and Fig. 5 various forms of the by-passing device.

The said illustrations refer to a fixed cylinder set at right angles to the center line of the engine and show a combination of links applicable for the proper transmission of the forces on the compensator-piston to the engine piston-rods. Any other suitable mechanism may, however, be substituted, and also the cylinder may be arranged oscillating

or two fixed or oscillating cylinders may be applied, symmetrically acting on one piston-rod.

As can be seen from Fig. 1, the cylinder 1, fitted with a relief-valve 2 and fixed to the engine-cradle, has in its lower part an opening 3, through which the motor fluid is continually admitted, exerting a fairly constant pressure on piston 4. The motor fluid may be supplied by a pump, (not shown in the drawings,) and which pump may be attached to the engine or worked independently, or the motor fluid may be supplied from any other source under constant pressure. Piston 4 is fitted with a port 5, which is constantly open to the working side of the piston, but the other end of which 6 is kept closed by the inner surface of the cylinder during the greatest part of the stroke. Only when the piston attains a certain length of the upstroke the mouth 6 of the port traveling over the upper edge of the cylinder-bore is laid open, thus forming a communication between the two sides of the cylinder, or, as shown in Fig. 3, in place of the ports in the piston the cylinder may be supplied with an outside pipe connection 12 and valve 13. In this case the opening 11 will have to be covered and laid open by the piston, while the other end remains constantly open. Valve 13 serves for regulating the size of the communication, or instead of ports valve 21 may be applied on the piston, as shown in Fig. 4, opened by an adjustable screw 22, if the piston comes high enough, or such a valve 23 may be arranged in the cylinder, as shown in Fig. 5, actuated by the piston and having a pipe communication 24 between the two sides of the cylinder 1.

Returning to Fig. 2, it will be observed that concentrically-arranged chambers 7 and 8 are provided, part of which being connectible by ports and valves 9 with the upper and another part by ports and valves 10 with the lower side of the cylinder, while a few of these chambers may be connected with either the upper or lower side of the cylinder.

The device is completed by the transmitting mechanism consisting of piston-rod 14, cross-head 15, links 16 and 17, the latter pivoted at 22 and connected with the former by bolt 18, which by means of the slide-piece

19 moves up and down in the yoke 20, connected to the engine piston-rods 21. As already mentioned, however, any other suitable mechanism may be substituted, care being taken that piston-rod 14 be adjustable in cross-head 15, so that by changing the length of the piston-rod 14 the opening 6 or 11 may be laid open sooner or later or the valves in Figs. 4 and 5 lifted earlier or later. The device as described above will now work as follows: Supposed the engine to be put in operation, the motor fluid having been admitted to the lower part of cylinder 1 by opening 3 exerts a constant pressure on piston 4 great enough to partly equalize the forces in the motor-cylinder of the engine. The latter will at first run short stroke; but by constantly supplying the motor fluid the stroke will lengthen out until piston 4 lays open opening 6 (or 11, Fig. 3) or opens the valves in Figs. 4 and 5, whereby the motor fluid is partly by-passed to the opposite side of the piston. The passage of the motor-fluid through the by-pass will continue, and the pressure on the opposite side will rise until the relief-valve 2 opens and exhausts part of the motor fluid to the atmosphere or back to the supply-pump. As soon as as much of the motor fluid is exhausted at each stroke through 2 as is supplied at the end of such stroke through 3 the state of equilibrium will be reached and kept up until any change occurs of the forces in the engine or of its speed. If for any reason the stroke of the main piston lengthens, the by-pass in the compensator remains open a longer time and supplies an excess of pressure on the top of the compensator-piston, which shortens the stroke. If the stroke becomes too short, the by-pass will not be open long enough to supply the normal quantity of pressure fluid on top of the compensator-piston, and the stroke will consequently lengthen. Thus by-passing will be diminished or increased until another state of equilibrium establishes itself, and so the compensator will always work in accordance with the forces acting on the engine.

This compensator may work with high or low pressures of the motor fluid, the difference of pressures on both sides driving it only; but the height of the pressures may be limited by setting the spring and lift of the relief-valve 2. For a satisfactory working it is further necessary that, depending on the nature or type of the engine, the driving pressures in the compensator vary differently during the travel of the compensator-piston. This can be attained by putting in communication one or more chambers 7, 8 with either the upper or the lower side of the compensator-piston, whereby the ratio of the expansion and compression of the motor fluid as compared with the variations in

volume effected by the movement of the piston can be changed on either of these sides.

What I claim as my invention, and desire to secure by Patent, is—

1. The combination, with a direct-acting engine, of a compensating cylinder having a piston which acts in opposition to the movement of the piston of the engine during the first part of the stroke and in conjunction therewith during the latter part of the stroke, and means for introducing a pressure fluid to both sides of the compensator-piston and for varying the pressures on opposite sides automatically as the stroke of the main engine varies.

2. The combination, with a direct-acting engine, of a compensating cylinder having a piston which acts in opposition to the movement of the piston of the engine during one part of the stroke and in conjunction therewith during another part of the stroke, the motor fluid being continually admitted to the working side of the compensator-piston, and means for admitting the motor fluid intermittently to the opposite side of the compensator-piston.

3. The combination, with a direct-acting engine, or a compensating cylinder having a piston which acts in opposition to the movement of the piston of the engine during one part of the stroke and in conjunction therewith during another part of the stroke, the motor fluid being continually admitted to the working side of the compensator-piston, and means for admitting the motor fluid to the opposite side of said compensator-piston intermittently and in quantities automatically controlled by the length of stroke.

4. The combination with a direct-acting engine, of a compensating cylinder having a piston which acts in opposition to the movement of the engine-piston during one part of the stroke and in conjunction therewith during another part of the stroke, and means controlled by the length of the engine-stroke for transferring fluid from the working side of the compensating piston to the opposite side to vary the compensating-cylinder pressure.

5. The combination with a direct-acting engine, of a compensating cylinder having a piston which acts in opposition to the movement of the engine-piston during one part of the stroke and in conjunction therewith during another part of the stroke, means for constantly admitting fluid on the working side of the compensating piston, and means controlled by the length of the engine-stroke for transferring fluid from the working side of the compensating piston to the opposite side to vary the compensating-cylinder pressure.

6. The combination with a direct-acting engine, of a compensating cylinder having a piston which acts in opposition to the move-

ment of the engine-piston during one part of the stroke and in conjunction therewith during another part of the stroke, means controlled by the length of the engine-stroke for transferring fluid from the working side of the compensating piston to the opposite side to vary the compensating-cylinder pressure, and an adjustable relief-valve on the back-pressure side of the compensating piston.

7. The combination with a direct-acting engine, of a compensating cylinder having a piston which acts in opposition to the movement of the engine-piston during one part of the stroke and in conjunction therewith during another part of the stroke, a port opened by the compensating piston to transfer more or less fluid from the working side of the compensating piston to the opposite side in accordance with the length of the engine-stroke, and an adjustable relief-valve on the back-pressure side of the compensating piston.

8. The combination with a direct-acting engine, of a compensating piston acting in opposition to the movement of the engine-piston during one part of the stroke and in conjunction therewith during another part of the stroke, means for applying motor fluid in opposition to the working pressure for adjusting the compensating-cylinder pressure, and means controlled by the length of the engine-stroke for transferring fluid from the working side of the compensating piston to the opposite side to vary the compensating-cylinder pressure.

9. The combination with a direct-acting engine, of a compensating cylinder having a piston acting in opposition to the movement of the engine-piston during one part of the stroke and in conjunction therewith during another part of the stroke, means controlled by the length of the engine-stroke for transferring fluid from the working side of the compensating piston to the opposite side at each stroke of the engine of uniform or greater length, and an outlet from the system for the escape of fluid to lessen the opposition to the working pressure.

10. The combination, with a direct-acting engine, of a compensating cylinder having a piston which acts in opposition to the movement of the piston of the engine during one part of the stroke and in conjunction therewith during another part of the stroke, the motor fluid being continually admitted to the working side of the compensator-piston, means provided for by-passing the motor fluid to the opposite side of said compensator-piston at a predetermined length of the stroke, means for regulating and relieving the pressure on the opposite side of the compensator-piston and means for regulating

the ratio of expansion and compression of the motor fluid on both sides of the compensator-piston.

65

11. The combination, with a direct-acting engine, of a compensating cylinder having a piston which acts in opposition to the movement of the piston of the engine during one part of the stroke and in conjunction therewith during another part of the stroke, the motor fluid being continually admitted to the working side of the compensator-piston only, said compensator-piston having a port, one end of which is constantly open to the working side while the other end remains covered by the inner surface of the compensating-cylinder during the greatest part of the stroke and is only laid open if it passes the upper edge of the cylinder-bore, thus putting the two sides of the piston in communication when the stroke attains a predetermined length.

70

12. The combination, with a direct-acting engine, of a compensating cylinder having a piston which acts in opposition to the movement of the piston of the engine during one part of the stroke and in conjunction therewith during another part of the stroke, the motor fluid being continually admitted to the working side of the compensator-piston only, means provided for by-passing the motor fluid to the opposite side of said compensator-piston at a predetermined length of the stroke, the upper or counter acting side of said compensator-cylinder being fitted with a relief-valve the load of which as well as its lift being made adjustable by hand.

80

13. The combination, with a direct-acting engine, of a compensating cylinder having a piston which acts in opposition to the movement of the piston of the engine during one part of the stroke and in conjunction therewith during another part of the stroke, the motor fluid being continually admitted to the working side of the compensator-piston, means provided for by-passing the motor fluid to the opposite side of said compensator-piston at a predetermined length of the stroke, and means for regulating and relieving the pressure on the opposite side of the compensator-piston, said compensator-cylinder being fitted with chambers, which may be connected by suitably-arranged valves with the working or the opposite side of the cylinder.
